United States Patent Office

Des. 202,163
Patented Aug. 31, 1965

202,163

FIRE HYDRANT

Earl W. Claus, St. Louis, Mo., assignor to Dresser Industries, Inc., Dallas, Tex., a corporation of Delaware

Filed Sept. 11, 1964, Ser. No. 81,413

Term of patent 14 years

(Cl. D91—3)

Fig. 1.

Fig. 2.

Fig. 3.

Fig. 4.

FIGURE 1 is a side elevational view of a fire hydrant showing my new design.

FIGURE 2 is a top plan view thereof;

FIGURE 3 is a front elevational view thereof; and

FIGURE 4 is a rear elevational view thereof.

A section of pipe is broken away in FIGURES 1, 3, and 4 to indicate indeterminate length.

I claim:

The ornamental design for a fire hydrant, as shown and described.
